United States Patent Office

Des. 189,588
Patented Jan. 10, 1961

189,588

COFFEE MAKER OR THE LIKE

Joseph Palma, Jr., Wheaton, Ill., assignor to Cory Corporation, Chicago, Ill., a corporation of Delaware

Filed Aug. 3, 1960, Ser. No. 61,619

Term of patent 14 years

(Cl. D44—26)

Fig. 1 is an isometric view of a coffee maker or the like embodying my new design.

Fig. 2 is a side elevational view of the coffee maker of Fig. 1.

Fig. 3 is a top plan view of the coffee maker of Fig. 1.
I claim:

The ornamental design for a coffee maker or the like, as shown.
